UNITED STATES PATENT OFFICE.

GEORGE W. STONE, OF MOBERLY, MISSOURI.

BOOKMARKER.

1,427,334.

Specification of Letters Patent. Patented Aug. 29, 1922.

Application filed March 29, 1922. Serial No. 547,942.

To all whom it may concern:

Be it known that I, GEORGE W. STONE, a citizen of the United States, residing at Moberly, in the county of Randolph, State 5 of Missouri, have invented a new and useful Bookmark; and I do hereby declare the following to be a full, clear, and exact description of the invention, such as will enable others skilled in the art to which it

10 appertains to make and use the same.

The invention relates to book marks, and has for its object to provide a book mark which is adapted to be slidably mounted on the outer edge of a leaf, and to be intermittently moved for uncovering lines during the reading operation, thereby allowing the reader to follow the lines without straining the eyes. The device is particularly adapted for use by persons having 20 defects of the eyes.

A further object is to provide the device with a slidable wedge at its outer end, which wedge forms means for gripping the edge of the page and holding the device 25 in any place to which it may be adjusted, for instance during a pause in reading or to mark the place for future reading.

With the above and other objects in view the invention resides in the combination and arrangement of parts as hereinafter set forth, shown in the drawings, described and claimed, it being understood that changes in the precise embodiment of the invention may be made within the scope 35 of what is claimed without departing from the spirit of the invention.

In the drawings:—

Figure 1 is a top plan view of the marker showing the marker attached to the leaf 40 of a book.

Figure 2 is a bottom perspective view of the marker.

Figure 3 is a vertical longitudinal sectional view through the marker.

45 Figure 4 is a perspective view of the slideable wedge.

Referring to the drawings, the numeral 1 designates the body of the marker and 2 the straight edge thereof, which straight 50 edge is adapted to be positioned beneath the lines of printing as shown in Figure 1 and to be intermittently moved during the reading operation. The end 3 of the body is provided with a depression 4, in which 55 the finger may be placed when moving the margin downwardly on the page 5 of the

book. When the marker is used on the opposite page 6 of the book, the edge 7 is intermittently moved downwardly beneath lines that are to be read. It will be seen 60 that during the reading operation the reader may easily follow lines on the pages of a book, and in such a manner that loss of the position during the reading will be obviated.

The outer end 8 of the body member 1 has extending downwardly from its opposite edges, downwardly and inwardly extending L-shaped flanges 9, which flanges form channels 10 of a wedge shaped with their narrow ends outwardly disposed, and in which channels 10 a page clamping wedge 11 is slidably mounted. When the wedge 11 is forced outwardly, the flange 12 carried by the wedge 11 engages the under side of the 75 page and jams and holds the same against the under face 13 of the body 1. However when the device is being used as a guard the wedge 11 is in inner position thereby allowing the device to slide on the page. When 80 the reader desires to mark the place the wedge 11 is forced outwardly and the sheet securely clamped in engagement with the under face of the body 1. To insure a positive clamping action, the taper of the channels 10 is reduced to a minimum thereby 85 allowing the wedge to easily wedge in the channels 10, in such a manner that it will be frictionally held. The wedge is limited in its movement to inoperative position by 90 means of a lug 14 secured at 15 to the under face of the body 1, which lug extends downwardly through an enlarged aperture 16 in the wedge 11. When the wedge 11 is moved inwardly to inoperative position the 95 wall 17 of the aperture 16 engages the lug 14 and stops the inward movement of the wedge thereby preventing loss or displacement of the wedge.

From the above it will be seen that a line guide and book mark is provided which is simple in construction and so constructed that it may be clamped and held in any position desired, in registration or adjacent the line of printing.

The invention having been set forth what is claimed as new and useful is:—

1. The combination with a line marker adapted to be intermittently moved over a sheet of paper, of a slideable wedge shaped 110 clamping member slidably mounted in wedge shaped channels in the outer end of

the marker and disposed on the under face of the marker and forming means for clamping a sheet against the under face of the marker.

5 2. A line guide and place marker comprising an elongated body member adapted to rest on a sheet, downwardly and inwardly extending flanges carried by the opposite edges of the body member adjacent 10 the outer edge of the body member and forming wedge shaped oppositely disposed channels having their narrow ends outwardly disposed, a wedge shaped member slidably mounted in said channel and provided with a centrally disposed enlarged

aperture, a lug carried by the body member and extending into the enlarged aperture and forming means for limiting the inward movement of the wedge shaped member and a flange carried by the inner face of said wedge shaped member and forming a clamping jaw cooperating with the underface of the body member.

20 In testimony whereof I have signed my name to this specification in the presence 25 of two subscribing witnesses.

GEORGE W. STONE.
